[57] CLAIM

The ornamental design for a container for hand sprayer, as shown.

DESCRIPTION

FIG. 1 is a left side elevational view of a container for hand sprayer showing our new design;

FIG. 2 is a front elevational view thereof;

FIG. 3 is a top plan view thereof;

FIG. 4 is a right side elevational view thereof;

FIG. 5 is a rear elevational view thereof; and

FIG. 6 is a bottom plan view thereof.

The broken line representation of a spray gun in FIGS. 1 through 6 is for purposes of illustration only.
